UNITED STATES PATENT OFFICE.

LUCY SPOHRER COIL, OF NEVADA, MISSOURI.

MATTRESS-HOLDER FOR INVALID-BEDS.

1,384,600.

Specification of Letters Patent. Patented July 12, 1921.

Application filed January 3, 1921. Serial No. 434,434.

To all whom it may concern:

Be it known that I, LUCY SPOHRER COIL, citizen of the United States, and resident of Nevada, county of Vernon, State of Missouri, have invented a certain new and useful Improvement in Mattress-Holders for Invalid-Beds, of which the following is a complete specification.

This invention relates to mattress holders for invalid beds and more particularly to beds having adjustable head and back rests, and the object of the invention is to equip a mattress with attachments for anchoring the mattress so that when the head and back rest is elevated the mattress cannot slip down the sloping portion thus formed.

With the object named in view, the invention consists in certain novel and peculiar features of construction and organization of parts as hereinafter described and claimed; and in order that it may be fully understood, reference is to be had to the accompanying drawing, in which:

Figure 1 is a top plan view of a mattress equipped with the devices of the invention.

Fig. 2 is a side elevation with the devices of the invention in use for preventing the elevated portion of the mattress from slipping downward.

In the said drawing, where like reference characters identify corresponding parts in all of the figures, 1 is the side rail of a bed, and 2 the pivoted head and back rest which can be swung to and secured in an inclined position, as indicated in Fig. 2. The particular means for holding the head and back rest in inclined position is not shown as it forms no part of the invention.

Resting on the bed and overlying the head and back rest is an ordinary mattress 3. Secured to each end of the mattress, but at opposite sides thereof, are a series of straps 4, which are preferably so stitched that they are capable of being swung away from the adjacent end portion of the mattress, but which for the greater portion of their length are stitched to the mattress cover so as to relieve the mattress of strain by distributing the same over a large portion of the mattress cover, and said straps are equipped at their loose or free ends with hooks 5.

In practice, the hooks at one end only, that is the head end perform any function, the straps at the opposite end functioning only when the mattress is reversed in position and turned over, to bring such straps at the head of the bed. By reference to Fig. 2, it will be seen that the straps at the head of the bed underlie the mattress and that their hooks engage the cross rail 6 of the head and back rest, so that when the latter is raised it will be impossible for the mattress to slip down the incline thus formed. The straps are not attached close to the extreme end of the mattress in order that it may be possible to tuck a sheet under the mattress and between the latter and the ends of the straps without interference thereby. It will also be understood that the straps nearest the side margins of the mattress will be stitched a certain distance therefrom, in order that the sheets may be tucked under the side edges of the mattress without interference by the straps.

From the above description it will be apparent that I have produced a device of the character outlined, which possesses all the features of advantage set forth in the statement of the object of the invention, and while I have described and claimed the preferred embodiment of the same, I reserve the right to make all changes properly falling within the spirit and scope of the appended claim.

I claim:

The combination with a holder and a mattress for support thereon, of a plurality of straps extending longitudinally of and underlying the mattress; the foot ends of the straps being secured to the mattress some distance from the head end thereof to permit a sheet, when spread over the mattress, to be fully tucked down over the head end thereof and back between such end and the said straps, and means attached to the opposite ends of the straps for detachable engagement with the head end of the holder.

In testimony whereof I hereunto affix my signature.

LUCY SPOHRER COIL.
